CLAIM

We claim the ornamental design for a partition, as shown and described.

DESCRIPTION

FIG. 1 is a top front/right perspective view of a partition, showing a first embodiment of our new design;

FIG. 2 is a front perspective view of the partition thereof;

FIG. 3 is a front view of the partition thereof;

FIG. 4 is a rear view of the partition thereof;

FIG. 5 is a left side view of the partition thereof, the right side view is a mirror image of the left side view of FIG. 5;

FIG. 6 is a top view of the partition thereof;

FIG. 7 is a bottom view of the partition thereof;

FIG. 8 is a top front/right perspective view of a partition, showing a second embodiment of our new design;

FIG. 9 is a front perspective view of the partition thereof;

FIG. 10 is a front view of the partition thereof;

FIG. 11 is a rear view of the partition thereof;

FIG. 12 is a left side view of the partition thereof, the right side view is a mirror image of the left side view of FIG. 12;

FIG. 13 is a top view of the partition thereof; and,

FIG. 14 is a bottom view of the partition thereof.

The broken lines are for the purpose of showing portions of the partition that form no part of the claimed design.

1 Claim, 10 Drawing Sheets
